US00D819578S

(12) **United States Design Patent** (10) Patent No.: **US D819,578 S**
(45) Date of Patent: **** Jun. 5, 2018**

(54) **HEAT DISSIPATING FIN**

(71) Applicant: **ENERMAX TECHNOLOGY CORPORATION**, Taoyuan (TW)

(72) Inventor: **Yen-Wen Su**, Taoyuan (TW)

(73) Assignee: **ENERMAX TECHNOLOGY CORPORATION**, Taoyuan (TW)

(**) Term: **15 Years**

(21) Appl. No.: **29/571,167**

(22) Filed: **Jul. 14, 2016**

(51) LOC (11) Cl. **13-03**

(52) U.S. Cl.

USPC **D13/179**; D14/439

(58) **Field of Classification Search**

USPC D13/179, 122, 182; D14/439, 433

CPC G06F 1/20; H01L 23/34; H01L 23/46; H05K 7/20154; H05K 7/20272; F28F 1/30; F28F 2215/00; F28D 1/0426

See application file for complete search history.

(57) **CLAIM**

The ornamental design for a heat dissipating fin, as shown and described.

DESCRIPTION

FIG. 1 is a perspective view of a heat dissipating fin showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is second perspective view showing the heat dissipating fin.

FIG. 9 is third perspective view showing the heat dissipating fin; and,

FIG. 10 is a perspective view showing the heat dissipating fins stacked on heat pipes of a heat sink.

The broken lines shown represent unclaimed subject matter and form no part of the claimed design.
